BATTERY TERMINAL

Eddie Robinson, Kansas City, Mo.

Application November 26, 1934, Serial No. 754,810

7 Claims. (Cl. 173—259)

This invention relates to electrical connectors and particularly it has for its object to provide a terminal connector for effecting electrical connection between a conductor cable and the terminal post of a storage battery or the like.

Another object is to provide a battery terminal so constructed as to substantially circumscribe the battery post when in the operative position and one that is easily positioned on and removed from the post.

A further object of the invention is the provision of a connector having an opening formed therethrough and a tongue extending into said opening, movable to cause a clamping effect between the post and connector.

Other features are simplicity and economy of construction, ease of operation and adaptability to conform to battery posts of different cross sectional shapes.

In the accompanying drawing, wherein similar parts are designated by like numerals throughout the several views:

Figure 1 is a side elevation of a battery terminal embodying this invention.

Fig. 2 is a plan view of the same.

Fig. 3 is a longitudinal, vertical section of the connector or terminal, detached from the post.

Fig. 4 is an end elevation of the connector, and,

Fig. 5 is a perspective view of the connector.

The battery post 10 is of any conventional type, but is here shown as of a frusto-conical shape, and is adapted to receive the cable terminal or connector 12.

The conductor cable 14 is secured in the connector 12 in any of the well known ways and as shown in the drawing, the exposed end of the drawing may be inserted in recess 16; then the spaced-apart legs are pressed together around the cable, after which the parts may be leaded or otherwise securely bound together so as to make a secure electrical connection.

The connector 12 is preferably cast, and is of a metal having good electrical conductivity, and since the contact between the post and connector is very important, special features have been provided whereby a large percent of the post surface is contacted by the connector. An opening 20 is formed through the connector 12, into which a tongue 22 projects. This tongue 22 is integral with the body of the connector and extends substantially across the opening and is shaped to conform to the side wall of the battery post. The portion 24 of the opening is shown as frusto-conical in shape and adapted to fit the post 10 as shown; however, it might be cylindrically or

otherwise shaped to properly fit posts of various shapes. The other portion 26 of the opening allows for movement of the tongue 22 to and from the post 10 during the tightening and loosening operations.

A set screw 28 is adapted to be secured into the threaded opening 30 formed through the side wall of 12 and to engage the outer side of tongue 20. When the connector has been positioned on the post as shown in Figs. 1 and 2, set screw may be 10 screwed tightly against tongue 22 and cause it to hug closely to post 10, and to substantially close the gap 32 between the end of the tongue and the inner side wall of 12.

To facilitate the removal of the connector from 15 the post the upper inner edge of the tongue is provided with a cutaway portion 34, thus forming a recess between the tongue and post, into which a tool, such as a screw driver may be inserted to pry the tongue away from the post. This cutaway portion may be of any form since the only requirement is that a recess be formed intermediate the inner wall of the tongue and the side wall of the post to permit the insertion of a wedging member whereby the tongue is separated 25 from the post.

While the preferred form of this invention has been shown and described, it is apparent that many modifications might be made without departing from the spirit of the invention.

30

What I claim is:

1. A battery cable terminal comprising a connector having an opening formed therethrough; a tongue integral with the connector, extending laterally from the inner wall of the conductor 35 into said opening to form, with the connector, battery post engaging walls; and adjustable means carried by said connector to force the tongue toward one of the walls of the connector and against a battery post when the terminal 40 is in place on such post.

2. A battery cable terminal comprising a connector having an opening therethrough; a bendable tongue integral with the connector extending transversely into said opening to form an 45 opening having a substantially frusto-conical shape; and adjustable means to bend said tongue in said opening, the wall of the connector extending continuously around the said tongue.

3. A battery cable terminal comprising a connector having an opening formed therethrough; a tongue extending into said opening to form a portion of said opening into a substantially frusto-conical opening to receive a battery post; a cutaway portion at the upper edge of said 55

tongue adjacent said post; and means for forcing said tongue against a battery post when the connector is in operative position thereon.

4. A battery cable terminal comprising a connector having an opening formed therethrough; a tongue integral with said connector, extending transversely into said opening, with its upper and lower edges respectively in the upper and lower planes of the connector; and adjustable means 10 to force the tongue against a battery post when the terminal is in place on a battery post, said connector and tongue forming post-engaging walls.

5. A battery cable terminal comprising a connector having means for engaging a conductor cable; an opening formed through said connector; a tongue integral with said connector and extending transversely into said opening; a set screw adjustably mounted in said connector 15 adapted to engage said tongue; and a cutaway portion formed at one side of the upper edge of said tongue.

6. A battery cable terminal comprising a cast metal connector having an opening formed there- 25 through to present a battery post engaging wall; an integral tongue projecting into said opening from one side of the connector and having its upper and lower edges in the plane of the upper and lower edges respectively of said connector 30 and the free end thereof spaced from the opposite side of said connector and presenting a

battery post engaging wall; a tapped opening formed through the connector; and a set screw in screwthreaded engagement with said tapped opening, projecting into said opening of the connector into engagement with the tongue, said tongue being bendable in one direction by the manipulation of said screw to force the tongue into engagement with the battery post. 5

7. A battery cable terminal comprising a cast metal connector having an opening formed there- 10 through to present a battery post engaging wall; an integral tongue projecting into said opening from one side of the connector and having its upper and lower edges in the plane of the upper and lower edges respectively of said connector 15 and the free end thereof spaced from the opposite side of said connector and presenting a battery post engaging wall; a tapped opening formed through the connector; and a set screw in screwthreaded engagement with said tapped opening, 20 projecting into said opening of the connector into engagement with the tongue, said tongue being bendable in one direction by the manipulation of said screw to force the tongue into engagement with the battery post, said tongue having a 25 cutaway portion at one edge thereof adjacent the battery post when in position to form therewith a tool engaging cavity whereby to bend the tongue in the opposite direction when removing the connector. 30
